UNITED STATES PATENT OFFICE.

WILLIAM P. NEWKIRK, OF PUEBLO, COLORADO, ASSIGNOR, BY DIRECT AND MESNE ASSIGNMENTS, OF ONE-FOURTH TO WASHINGTON D. ISGRIG AND ONE-FOURTH TO CHARLES L. CROOKS, BOTH OF PUEBLO, COLORADO.

PORTABLE DERAILING DEVICE.

1,106,155.

Specification of Letters Patent.

Patented Aug. 4, 1914.

Application filed April 22, 1913. Serial No. 762,844.

To all whom it may concern:

Be it known that I, WILLIAM P. NEWKIRK, a citizen of the United States, and a resident of Pueblo, in the county of Pueblo and State of Colorado, have invented a new and useful Improvement in Portable Derailing Devices, of which the following is a specification.

My invention is an improvement in portable derailing devices, especially adapted for use in connection with car inspectors' and repairers' blue flags, and has for its object to provide a device of the character specified, capable of being easily transported, adapted to be connected to a rail at any desired point, and having means for checking and derailing a car at any predetermined point to protect car repairs, inspectors, or track ends, and having means for supporting a flag or other signal.

In the drawings:—Figure 1 is a perspective view of the device in place, Fig. 2 is an end view of the derailing device with the rail in section, Fig. 3 is a side view from the inner side of the rail, Fig. 4 is a plan view of the device in place, and Fig. 5 is a side view on the outer side of the rail.

The present embodiment of the invention is shown in connection with a rail 1, supported by the usual ties 2, and the device comprises a casting or forging, consisting of a plate 3, adapted to rest on the tread of the rail and of a width corresponding to the width of the tread, each end of the said plate being beveled or inclined as indicated at 4 and 4^a respectively, to provide an easy approach from the rail to the top of the plate. At the end adjacent to the incline 4^a, the plate is extended as indicated at 5, the said extension being of much less thickness than the end 4, and a flange 6 is provided at the said end, the said flange extending from the highest portion of the plate to the outer end of the extension 5, and the said flange 6 is inclined with respect to the rail as indicated more particularly in Fig. 4. The plate is also provided with a depending web 7 on the inner side of the rail, the said web being of a length to extend from the tread of the rail, that is, from the under face of the plate 3, to the base flange of the rail, and the lower edge of the said web rests upon the base flange as shown more particularly in Fig. 2.

The flange 6 extends from the point well inside of the inner edge of the base flange of the rail to approximately the center of the tread of the rail, as shown in Figs. 2 and 4, and the upper face of the web 7 is grooved as indicated at 8, the said groove extending from the beginning of the web and inclining upward to the level of the upper face of the extension 5, in order to gradually lift the flange of a car wheel to the level of the upper face of the extension 5, and above the tread of the rail.

The plate 3 is provided with an extension 9 on the opposite side of the rail from the web 7, and the said extension has a depending web 9^a fitting outside of the tread of the rail, the lower end of the said web being curved inwardly as indicated at 16 to engage the web of the rail a short distance below the tread and on the outer face of the rail. The web is provided at each end with an outwardly extending lug 10 and 11 respectively, each of the said lugs being perforated as shown.

A clamping jaw 12 is hinged or pivoted to the lug 10, by means of a bolt 13, the said bolt passing through registering openings in the upper end of the jaw and in the upper end of the lug, and a nut 14 engages the bolt to hold it in place.

The lug 10 extends the full width of the web 9^a, and at its lower end the said lug is provided with a perforated ear 17. The gripping jaw 12 curves downwardly and inwardly, the free end thereof being adapted to engage the web of the rail below the point of engagement of the portion 16 of the web 9^a, and when in such position an opening 18 in the said jaw will register with the opening of the ear 17, and the said openings are adapted for engagement by the shackle of a padlock 19, to prevent outward movement of the gripping jaw.

The lug 11 has connected therewith one end of a chain 20, or the like flexible member, and the other end of the chain is adapted to be secured to the tie 2 by means of a spike 21 or the like. On the inner side of the rail, the flange 6 is provided with an integral inwardly extending vertical bearing 22, and the said bearing is adapted to receive a staff 23, provided at its upper end with a plate 24, having thereon a legend as for instance, the word "Stop."

The device is placed on the rail by fitting the plate 3 on the tread thereof with the web 7 depending on the inner side of the rail and with the web 9^a depending on the outer side. 5 The portion 16 of the web 9^a engages the outer face of the web of the rail, and when the gripping jaw 12 is secured to the lug 11 by the pad lock 19, the said device is locked firmly in place on the rail. The spike 21 is 10 driven through the last link of the chain 20, thus holding the device from longitudinal movement with respect to the rail. When a car engages the inclined end 4 of the plate 3, the wheel is lifted above the tread and the 15 flange thereof enters the groove 8 at the top of the web 7. As the wheel travels along the plate 3, the flange 6 by its engagement with the flange of the car wheel, gradually moves the wheel laterally over the rail, so that when 20 the wheel leaves the device, the car is derailed, that is, the leading wheels of the car are off the rails. If the movement of the car continues the rear wheels of the front truck will also be derailed. The derailing 25 of the car however, will check the movement of the same.

The legend on the plate 24 is a sufficient warning to persons in charge of rolling stock to stop the same before engagement with the 30 derailing device. It will be evident that the device may be easily transported and may be applied at any position on the rail. The only thing necessary to permit the displacement of the device from the rail is to release the chain and unlock the padlock to 35 permit the gripping jaw 12 to swing outwardly. Even without the chain, the device could not slip on the rail to any great distance for the engagement of the web 7 with 40 the spikes would check the longitudinal movement of the device. It will be noticed that the web 7 is reinforced at the end 4 of the device by a vertical rib 25, the said rib extending the full length of the web.

45 The improved device may be placed a distance of 30 feet from the car or other object to be protected and will insure perfect protection by derailing an approaching car. Thus a large amount of said track could be 50 saved for ordinary use. The device is especially adapted for car repairs, since it is compact and of small weight, and quickly applied or disengaged from the rail.

The usual protection for car repairs is a 55 blue flag on a staff, usually of iron having a point and stuck lightly into a tie. Such device is easily displaced and many car repairers are killed and injured through failure to keep the flag in a visible position.

60 With the improved device there is no possibility of a car or train of cars passing the derailing device a sufficient distance to engage the car protected. The device is placed on the rail, from the outer side, the portion 65 16 of the web 9^a being first engaged beneath

the tread, with the depending web 7 almost horizontal. The device is then turned over into place on the rail. It will be noted that there is a sufficient space between the portion 16 of the derailler and the under face of the 70 tread, to permit this movement.

I claim:—

1. A device of the character specified, comprising a plate adapted to be arranged on the tread of a rail longitudinally of the rail, 75 said plate having each of its ends inclined or beveled and having at each side edge a depending web, one of the said webs extending into engagement with the base flange of the rail and the other curving inwardly at 80 its lower end to engage the web at the outer side of the rail and below the tread, said device having an upstanding flange inclined with respect to the rail to deflect the flange of a car wheel from the inner to the outer 85 side of the rail, said device having a groove at one end between the flange and the plate, the web at the outer side of the rail having a transverse lug at each end thereof, each of the said lugs being perforated, a chain connected with one lug and a gripping jaw connected with the other, said jaw having an opening at its upper end registering with the opening of the lug, a bolt traversing the said opening to hinge the jaw to the lug, said 95 jaw curving downwardly and inwardly at its lower end to engage the web of the rail, the jaw and the adjacent lug having registering openings for engagement by the shackle of a pad lock when the said jaw is 100 in engagement with the web of the rail.

2. A device of the character specified, comprising a plate adapted to rest on the tread of a rail, said plate having each of its ends inclined or beveled toward the rail and 105 having at each side edge a depending web, one of the said webs extending into engagement with the base flange of the rail and the other curving inwardly at its lower end to engage the web at the outer side of the rail and below the tread, said device having an upstanding flange inclined with respect to the rail and extending across the plate, the web at the outer side of the rail having a lug at each end thereof, a chain connected 110 with the lug and adapted for connection with the tie at the other end, a gripping jaw pivoted to the other lug, said jaw curving downwardly and inwardly at its lower end to engage the web of the rail near the base 115 flange, the jaw and the adjacent lug having registering openings when the said jaw is in engagement with the rail for receiving a locking means.

3. A device of the character specified, 125 comprising a plate adapted to rest on the tread of a rail, said plate having each of its ends inclined or beveled toward the rail and having at each side edge a depending web, one of the said webs extending into engage- 130

ment with the base flange of the rail and the other curving inwardly at its lower end to engage the web at the outer side of the rail and below the tread, said device having an upstanding flange inclined with respect to the rail and extending across the plate, a chain connected with the web at the outer side of the rail at one end thereof, a locking jaw hinged to the other end, said jaw curving downwardly and inwardly to engage the web of the rail, and means for locking the jaw in engagement with the web of the rail.

4. A device of the character specified, comprising a plate having its ends beveled and provided at each side edge with a depending web, one of the said webs being of lesser length than the other and curving inwardly at its lower end, said device being adapted to rest upon a rail with the webs depending on opposite sides thereof, the longer web being adapted to engage the base flange of the rail, said device having an upstanding flange inclined with respect to the rail, and a gripping jaw pivoted to the shorter web, said jaw being adapted to engage the rail below the engagement of the web, and means for locking the jaw in place.

5. A device of the character specified, comprising a plate having its ends beveled and provided at each side edge with a depending web, one of the said webs being of lesser length than the other and curving inwardly at its lower end, said device being adapted to rest upon a rail with the webs depending on opposite sides thereof, the longer web being adapted to engage the base flange of the rail, said device having an upstanding flange inclined with respect to the rail, and a gripping jaw pivoted to the shorter web, said jaw being adapted to engage the rail below the engagement of the web, means for locking the jaw in place, and means for anchoring the said device to a tie.

30 6. A device of the character specified, comprising a plate having its ends beveled

and provided at each side edge with a depending web, one of the said webs being of lesser length than the other and curved inwardly at its lower end, said device being 35 adapted to rest upon a rail with the webs depending on opposite sides thereof, the longer web being adapted to engage the base flange of the rail, said device having an upstanding flange inclined with respect to 40 the rail, and a gripping jaw pivoted to the shorter web, said jaw being adapted to engage the rail below the engagement of the web, and means for locking the jaw in place.

7. A device of the character specified, 45 comprising a plate having its ends beveled downwardly and having depending webs at each side thereof, said plate being adapted to seat on a rail with the webs depending on each side of the rail, one of the said webs 50 being of a length to engage the said base flange of the rail, and the other web curving inwardly to engage the web of the rail below the tread, said plate having an inclined upstanding flange, and means for locking the 55 said device to the rail.
